DISPLAY HANGER

Edward E. Schaefer, 1534 Park Ave., River Forest, Ill.

Filed Aug. 15, 1958, Ser. No. 755,221

2 Claims. (Cl. 211—45)

This invention relates to hangers and more particularly relates to improvements in display hangers of the type used to display finished dry goods such as bedspreads, draperies, or the like.

One of the problems encountered in displaying larger sized finished dry goods such as bedspreads and draperies is that of providing a hanger construction which permits a rapid and simple mounting of the goods on the hanger and removal therefrom without having to thread the goods through the hanger. Heretofore, the typical closed loop type hanger required careful threading of the goods through the hanger loop which was time consuming and often resulted in the goods becoming soiled or wrinkled.

The present invention offers a solution to this problem in the form of an improved display hanger of the type having separable crossbar and support members which permit the hanger to be slipped around or removed from a bedspread or like article without appreciably moving the article relative to the hanger.

Accordingly, it is a general object of the present invention to provide an improved display hanger for finished dry goods articles, such as bedspreads, draperies, and the like.

Another object of the present invention is to provide an improved display hanger adapted for displaying bulky dry goods articles or the like, said hanger being constructed and arranged so as to be rapidly engageable and disengageable therefrom without the necessity of threading the articles through the hanger.

Other objects and advantages of the invention will become apparent in the following detailed description and accompanying sheet of drawings, in which:

Fig. 1 is an elevational view of a display hanger constructed according to the principles of the present invention;

Fig. 2 is a top plan view of the display hanger of Fig. 1;

Fig. 3 is a transverse sectional view taken along the line 3—3 of Fig. 1;

Fig. 4 is an end view of the display hanger of Figs. 1 and 2, as viewed from the left thereof;

Fig. 5 is an enlarged fragmentary sectional view taken along the line 5—5 of Fig. 4;

Fig. 6 is an end view of the display hanger of Figs. 1 and 2, as viewed from the right thereof;

Fig. 7 is an enlarged fragmentary sectional view taken along the line 7—7 of Fig. 6;

Fig. 8 is a view similar to Fig. 7, but showing an alternate end connection construction at the right end of the hanger; and

Fig. 9 is an end view as seen along the line 9—9 of Fig. 8.

Briefly described, the present invention comprises an improved display hanger for bulky dry goods articles, such as bedspreads, draperies, and the like, having a separable support member that includes an expandable shank hook and crossbar which permits the hanger to be slid or moved around the object to be displayed therefrom without the necessity of threading the article through the hanger loop and over the crossbar.

2

To this end, the crossbar of the hanger includes novel projecting pin and socket type end connections for engagement with the support member thereof, the latter being formed with complementally shaped loop and projecting pin type ends for engagement with the crossbar end connections. The support member is of a one-piece wire construction bent to form an integral double thickness loop or centrally disposed hook, the shank portions thereof being expandable and extended horizontally as bars. The bars extend generally parallel to the crossbar in spaced relation and the ends thereof depend downwardly and terminate as a loop and an inturned end for engagement with the end connections at each end of the crossbar. The resiliency of the wire material of the support member is such as to permit the latter to be distorted or elongated so that the looped end thereof becomes disengaged from the outwardly projecting pin of the crossbar end connection, thereby to separate the support member and permit the hanger to be moved into engagement around an article to be supported and displayed therefrom.

In Figs. 1 and 2, a display hanger 10 is illustrated which is constructed according to the principles of the present invention and which accomplishes the aforementioned objects. The display hanger 10 generally comprises a tubular article supporting crossbar 11 and a disengageable or separable support member 12 which includes an integral upright hook portion 13 having laterally disposed bar portions 14 extending oppositely from the base of the hook 13. A pair of end connections 15 and 16, at the left and right ends of the crossbar 11, respectively, provide a detachable connection of the support member 12 to the crossbar 11, as will hereinafter be more fully described.

The crossbar 11 is preferably tubular in shape and may be formed from metal, plastic, or other materials having sufficient strength to support the larger sized dry goods articles. The crossbar 11 includes a pair of axially spaced tubular sleeves or bushings 17 (Fig. 3) formed from rubber or similar material, and non-rotatably secured to the crossbar 11. The external surfaces of the sleeves 17 may be ridged, as at 18, to prevent an article from sliding off of the crossbar 11 when supported thereon. It will be understood that the number, spacing, and construction of the sleeves 17 may be varied as required for a particular hanger size.

As will be seen from Figs. 1 and 2, the support member 12 is of a one-piece resilient wire construction which is bent to form an integral double thickness hook 13 and laterally extending bar portions 14. The hook 13 is formed by bending the support member wire into a congruent pair of superposed loops, each loop being indicated respectively at 13a and 13b, and having respective shank portions 21a and 21b, which extend laterally as bar portions 14. The loops 13a and 13b and the shank portions 21a and 21b are normally in substantially congruent alignment when the support member 12 is in assembled relationship with the crossbar 11, these portions being resiliently movable by distortion in scissor-like fashion to permit engagement and disengagement of the support member 12 at the end connection 15 from the crossbar 11.

The outer ends 22 of the bar portions 14 are bent downwardly and have their remote lower ends formed to complementally engage the end connections 15 and 16. In this instance the left end 22 is formed with a loop 23 and the right end is formed with an inturned end 24 (Fig. 7) for engagement with the end connections 15 and 16, respectively. The bar portions 14 are thus maintained in vertically spaced relation from the crossbar 11.

As will be seen in Figs. 4 and 7, the loop 23 preferably has a diameter somewhat less than the diameter of the crossbar 11, and the inturned end 24 is insubstantial axial

alignment with the axis of the crossbar 11. The axial spacing between the downturned ends 22 is such that the inturned end 24 and loop 23 are normally biased inwardly against the end connections 15 and 16 with a slight compressive force, thereby preventing accidental disengagement.

As best shown in Fig. 5, the end connection 15 preferably comprises a plug-like member of metal or plastic having a cylindrical body portion 26, an annular collar or shoulder portion 27, and an outwardly projecting pin-like portion 28. The body portion 26 has a tight press-fit with the interior of the tube 11 and the collar 27 abuts the annular end face of the tube 11. The pin portion 28 is rigid with the body 26 and has a diameter somewhat less than the inside diameter of the loop 23 so that the loop 23, is freely engageable and disengageable therefrom. The length of the pin portion 28 is such as will permit its extension through the loop 23 when the support member 12 is engaged with the crossbar 11, and to permit disengagement from the loop 23 when it is desired to display an article on the hanger.

As will be seen from Figs. 6 and 7, the end connection 16 comprises a tubular plug-like member or bushing 31 having a press fit in the end of the tube 11 and comprising a cylindrical wall portion 32 and a base 33. A cap member or ferrule 34 of plastic or the like is fitted over the end of the crossbar 11. The base 33 of the plug-like member 31 and the cap member 34 each have central bores 36 and 37, respectively, for receiving and journaling the inturned wire end 24. It is to be noted that the inturned end 24 has an axial length sufficient to insure an engaged supporting relationship in the bores 36 and 37 throughout the normal range of movement of the support member 12. The inner end of the inturned end 24 may be staked or enlarged in order to prevent disengagement from the end connection 16, if desired.

The operation of the display hanger 10 is as follows. Assuming that the hanger 10 is in an initial assembled position, as shown in full lines in Fig. 1, and it is desired to display a bedspread or drapery therefrom without threading the latter through the hanger 10, it is first necessary for an operator to disengage the wire support 12 from the crossbar 11. This may be accomplished by concurrently grasping the tube 11 and the left-hand bar portion 14 or its downturned end 22 at the left end of the hanger and spreading the two away from each other such that the loop 23 is forced outwardly on the pin portion 28, and disengaged therefrom. As a result, the shank portions 21a and 21b of the hook are resiliently expanded as shown in the lowermost dotted line position in Fig. 1. The loop 23 is thus disengaged from the pin portion 28 and the support member 12 can be pivoted about the end connection 16 to the uppermost dotted line position illustrated in Fig. 1. The aforementioned resilient expansion is afforded by the one-piece wire construction of the support member 12 and the double thickness superposed loop and shank portions of the hook 13. When thus disengaged, the crossbar 11 may then be slid under or moved around an article to be displayed therefrom without disturbing the article from its previous position, such as on a display rack or while folded on a table. Once the article has been positioned over the crossbar 11, the loop portion 23 is reengaged with the pin 28. The hanger 10, together with the article supported thereon may then be moved to any desired display position and supported by the hook 13 in a well known manner.

Referring now to Figs. 8 and 9, an alternate end construction 40 for the right end of the crossbar 11 is illustrated, the end connection 40 being arranged to prevent relative rotation between the crossbar 11 and support

5 member 12. The end connection 40 comprises a plug-like member having a cylindrical body portion 41 press fitted in the tube 11 and a collar portion 42 of somewhat greater diameter than the outside diameter of the crossbar 11. The body portion 41 and collar portion 42 are centrally axially bored, as at 43, to receive the inturned wire end 24 in a manner similar to the arrangement shown in Fig. 7 of the first-described embodiment.

10 The outer end face of the collar 42 is formed with a diametrical groove or slot 44, which preferably has a depth somewhat greater than the radius of the wire end 24. It will be apparent that the inward resilient force of support member 12 at the ends 22 will serve to seat the depending end 24 in the slot 44 and thereby prevent rotation of the crossbar 11 once these parts are engaged in their Fig. 8 position. The end connection 40 thus prevents rotation of the tube 11 relative to the support member 12 and is thus particularly advantageous where heavy articles are to be displayed which might otherwise roll off of the crossbar 11 due to an uneven positioning thereon.

15 While only certain specific embodiments of invention have been described, it should be understood that other modifications and variations may be effected without departing from the scope of the invention as set forth in the appended claims.

20 I claim:

1. A display hanger comprising an elongated crossbar having an axial opening at one end thereof and a reduced diameter axial projection extending rigidly from the opposite end thereof, and a supporting frame comprising a single piece of resilient wire doubled centrally upon itself and curved to provide a normally superposed but resiliently spreadable double hook portion for the hanger, said wire extending outwardly in opposite directions from the 25 base of said hook portion generally parallel to said crossbar and thence laterally toward said crossbar, one end portion of the wire being formed into a substantially closed loop of smaller diameter than said opposite end of said crossbar for receiving and encircling said axial projection and the other end portion of said wire being inturned and extending axially into said opening in said one end of said crossbar, the distance between the laterally extending portions of the wire being such that said loop and the inturned end portion of the wire are normally biased 30 axially inwardly against the respective ends of said crossbar for normally retaining the crossbar and frame in fully connected relation and resisting accidental separation thereof, and said double hook portion being resiliently spreadable from its normally superposed relation for 35 axially displacing said loop outwardly and disengaging the same from said projection.

40 2. The structure of claim 1 further characterized in that said crossbar comprises a tubular member having a pair of plug-like members fitted in its opposite ends, one of said members being axially bored to receive the inturned end of said wire and the other of said members being formed with an integral reduced diameter axial extension providing said projection.
